UNITED STATES PATENT OFFICE.

ELLEN R. WEBB, OF DENVER, COLORADO.

DESIGN FOR A TOY.

Application filed December 2, 1921. Serial No. 519,521. Term of patent 7 years.

To all whom it may concern:

Be it known that I, ELLEN R. WEBB, a citizen of the United States, residing at Denver, in the county of Denver and State of Colorado, have invented a new, original, and ornamental Design for Toy, of which the following is a specification.

Reference being had to the accompanying drawing, forming part thereof,

Figure 1 is a side elevation of a toy showing my new design, and

Figure 2 is a perspective view showing the opposite face of the toy illustrated in Figure 1.

I claim:

The ornamental design for a toy, as shown,

ELLEN R. WEBB.
